WIRELESS RECEIVING SYSTEM

Application filed August 6, 1927. Serial No. 211,120.

This invention relates to a wireless receiving system.

In wireless receiving systems, it has been heretofore proposed to reflex the audio frequency energy through the tuned radio frequency tubes. These systems however have not proven wholly satisfactory for they disturb the sharply tuned circuits of the tubes and prevent an efficient functioning of the system. In addition to this, the tuned circuits of the several tubes cause radiation to occur from the antenna with consequent disturbance to other receiving sets.

This invention is designed to overcome the defects noted above and objects of such invention are to provide a novel form of radio receiving system in which the tuned radio frequency circuits of the tubes are not disturbed, but in which untuned tubes are placed between the tuned radio frequency tubes and the audio frequency energy reflexed through the untuned tubes without disturbing any of the tuned circuits.

Further objects are to provide a radio receiving system in which the untuned tubes serve not only as radio frequency amplifiers, but also as audio frequency amplifiers. It is well known that the tubes with their untuned circuits do not function as efficiently as radio frequency amplifiers as the tubes with tuned circuits. However, this invention utilizes such amplification as occurs for the radio frequency, but also loads these untuned tubes up with the audio frequency energy so as to secure a greater over-all efficiency than has heretofore been possible without increasing the number of tubes. In other words, objects of this invention are to provide a radio receiving system in which the untuned tubes are selectively picked out for the audio frequency amplification without disturbing the tuned tubes, although the untuned tubes are also employed in the capacity of radio frequency amplifiers.

Further objects are to provide a radio receiving system having the characteristics enumerated above in which there is no radiation from the antenna although the system may be sharply tuned and may work at its maximum efficiency.

A further object is to provide a radio receiving system in which the antenna effect will not disturb any of the tuning condensers so that antennæ of different lengths may be connected up to the sets without any change in the setting.

Embodiments of the invention are shown in the accompanying drawings in which:

Figure 1 is a view showing diagrammatically one form that the invention may take in which the audio frequency energy is reflexed through the untuned tubes which are selectively picked out.

Figure 2 is a diagrammatic view showing a further form of the invention in which the untuned tubes are used for reflexing the audio frequency energy, but in which the reflexing is done in an inverse manner.

Referring to Figure 1, it will be seen that the tubes are numbered 1 to 8 inclusive. The antenna 9 is connected through the coil 10 to the ground 11 and opposite ends of the coil 10 are connected to the grid 12 and the negative side of the filament 13 of the first tube 1. The plate 14 of this tube is connected to the primary 15 of a radio frequency transformer whose secondary 16 has its ends connected to the grid and filament of the tube numbered 2. A variable tuning condenser 17 is bridged across the coil 16.

The plate of the tube 2 is connected to the primary 18 of a second radio frequency transformer whose secondary 19 has one end connected to the grid of the tube 3. If desired, the coil 18 may be used as a radio frequency choke for the plate circuit of the tube 2 and a condenser 20 may be connected between the plate of the tube 2 and the grid of the tube 3. If desired, the condenser and transformer may both be used as shown in the figure.

The other end of the secondary 19 of the radio frequency transformer is connected to one side of the secondary 21 of an audio frequency transformer. The other side of this audio frequency transformer secondary is connected to the negative side of the filament of the tube 3, as indicated. Also, it is to be noted that a radio frequency bypass condenser 22 is bridged across the secondary 21.

of the audio frequency transformer. The primary 23 of the transformer is provided with a bridging condenser 24 which may be of large capacity and the primary is connected in a manner hereinafter described for transmitting audio frequency energy to the tube 3 from another portion of the system.

It is to be noted that the grid circuit of the tube 3 is untuned. The tube 3 has its plate connected through the primary 25 of a radio frequency transformer and through the primary 26 of an audio frequency transformer to the point 27 of the B battery indicated by the reference character B in the figure. Preferably, a condenser 28 is bridged across the terminals of the primary 26. The secondary 29 of the radio frequency transformer associated with the plate of the tube 3 is connected at one end to the grid of the tube 4 and at its other end to the filament of such tube. It is bridged by means of a variable condenser 30 so that the grid circuit of the tube 4 may be tuned.

The plate of the tube 4 is connected through the primary 31 of a radio frequency transformer to the point 27 of the B battery. Preferably, a main busbar 32 is employed, as shown in Figure 1, and connected to the plate circuit of the several amplifying tubes, as will appear as the description proceeds.

The secondary 33 of the last described radio frequency transformer is connected to the grid of the tube 5. If desired, a condenser 34 similar to the condenser 20 may be also employed. This condenser as well as the condenser 20 may act as a neutralizing condenser, if desired, or the coils 19 and 33 may be omitted and the condensers 20 and 34 will then act as stopping condensers and transmit radio frequency energy. The other end of the transformer secondary 33 is connected to one end of the secondary 35 of the audio frequency transformer whose primary is indicated by the reference character 26.

Preferably, a bypassing condenser 36 is bridged across the terminals of the secondary 35. It is to be noted that the other end of the secondary 35 is connected to the negative busbar 37. The plate of the tube 5 is connected through the primary 38 of a radio frequency transformer to one end of the primary 39 of an audio frequency transformer. The other end of the primary 39 is connected to the busbar 32 and from thence to the point 27 of the B battery. Preferably, a bypass condenser 40 is provided between the terminal of the audio frequency primary 39 and the busbar 32 in order to bypass radio frequency energy. The last described radio frequency transformer has its secondary 41 connected to the filament and grid of the tube 6. Further, this secondary is connected to the variable tuning condenser 42 so that the grid circuit of the tube 6 may be tuned.

The plate of the tube 6 is connected to one

end of the primary 43 of a radio frequency transformer and the secondary 44 of such transformer is connected to the grid and filament of the detector tube 7. The usual grid condenser and leak is employed in this circuit. The secondary 44 is bridged by means of the variable tuning condenser 45. The plate of the detector tube 7 is connected by means of the conductor 46 with one side of the primary 23 of the first described audio frequency transformer. The other side of the primary is connected to the point 47 of the B battery so as to secure the requisite voltage for the detector tube. It is to be noted that the primary 39 of the last audio frequency transformer is associated with the secondary 48 of such transformer, and such secondary is connected to the grid of the power tube 8 at one end. The other end of the secondary is connected to the point 49 of the biasing battery or C battery indicated by the letter C in the figure. The positive side 50 of such battery is connected to the negative filament busbar 37.

The plate of the power tube 8 is connected to one side of an audio frequency choke coil 51, the other side of such coil being connected to the point 52 of the B battery to secure the voltage for the plate circuit of the power tube. A stopping condenser and a translating device indicated by the reference characters 53 and 54, respectively, are connected to opposite ends of the audio frequency choke coil 51. The translating devices may obviously be a telephone receiver or a loud speaker, or any other suitable device. The purpose of the condenser 53 is to prevent the impressing of the high voltage upon the terminals of the translating device and to avoid the necessity of continuously passing the plate current therethrough.

It is to be noted that a suitable filament battery as indicated by the reference character A is employed and a single rheostat 55 may be used for simultaneously controlling all of the filaments.

The condensers 17, 30, 42, and 45 are tuned sharply to the desired wave length and it is apparent that these condensers may be either simultaneously tuned or individually tuned. In addition to this, it is to be noted that any type of coupling may be employed between the tubes. Also, it is apparent that instead of using radio frequency transformers between the tubes 2 and 3 and the tubes 4 and 5, that the coils 18 and 31 may be used as radio frequency chokes and the condensers 20 and 34 may be used to pass the amplified radio frequency energy to the succeeding tube. Further, if this is done, it may be found desirable to omit the coils 19 and 33 although their use is preferred.

In using the system, it is apparent that the antenna effect does not influence any of the tuning condensers and consequently antennæ

of different lengths may be connected to different sets without disturbing their tuning.

When the system is in operation, the radio frequency energy amplified by the tube 1 is passed to the tuned circuit for the tube 2 and is again amplified and passed to the untuned circuit of the tube 3. From thence, it passes to the tuned circuit of the tube 4 and from thence to the untuned circuit of the tube 5. The tube 5 passes the radio frequency energy to the tuned circuit of the tube 6 and to the grid circuit of the detector tube 7. This grid circuit may be either tuned or untuned for the detector tube 7. The audio frequency energy is passed through the primary 23 of the first audio frequency transformer. The secondary of the transformer supplies audio frequency energy to the grid of the tube 3. It is to be noted that the plate circuit 20 of the tube 3 includes the primary 26 of the next audio frequency transformer and, consequently, the audio frequency energy is passed through such primary. From the secondary 35 of this transformer the audio frequency energy passed to the grid of the tube 5 and from the plate of such tube passes through the primary 39 of the last audio frequency transformer. The secondary 48 of such transformer is connected to the grid of the power tube.

It is apparent from the description and the drawings that the untuned tubes are picked out selectively and the audio frequency energy is passed only through such tubes. It is not passed through the tuned tubes and consequently does not disturb such tubes.

It is apparent therefore that the over-all efficiency of the system is very much increased as the untuned tubes, although serving as radio frequency amplifiers, are employed in a double capacity and are also used as audio frequency amplifiers. It is apparent that the untuned tubes are not so efficient as radio frequency amplifiers as the tuned tubes, but they are nevertheless also called upon to act as audio frequency amplifiers. The consequence of this is that the over-all efficiency of the system is very greatly increased without increasing the number of tubes. In addition to this, there is no possible chance of radiation from the antenna.

In the form of the invention shown in Figure 2, the same numbering for the tubes has been followed, tubes 1 to 6 being amplifier tubes, tube 7, a detector, and tube 8, a power tube. Also, the A and B batteries are indicated by reference characters A and B, and the C or biasing battery for the power tube indicated by the reference character C.

In this form of the invention, the tube 1 has its grid and filament connected to opposite ends of the coil 10 in the antenna circuit. Its plate is connected through the secondary 56 of a radio frequency transformer to the positive busbar 57 connected to the point 58 of the

B battery. The secondary 59 of the radio frequency transformer is connected to the filament and grid of the tube 2 and is bridged by the variable tuning condenser 60. The plate of the tube 2 is connected through the radio frequency choke coil 61 to the busbar 57. A condenser 62 is connected from the plate of the tube 2 to the grid of the tube 3 and also it is to be noted that the secondary 63 of an audio frequency transformer has one end connected to the grid of the tube 3. Its other end is connected through a biasing battery or auxiliary C battery 64 to the filament of the tube 3. The primary of this audio frequency transformer is indicated by the reference character 65 and its connections will be described hereinafter. The tube 3 has its plate connected through the secondary 66 of a radio frequency transformer, the secondary 67 of such transformer being connected to the grid and filament of the tube 4, and bridged by a condenser 67.

The plate of the tube 4 is connected through a radio frequency choke coil 68 to the busbar 57. A condenser 69 is connected from the plate of the tube 4 to the grid of the tube 5. Further, it is to be noted that the secondary 70 of an audio frequency transformer is connected to the grid of the tube 5 and to the negative side of a second auxiliary C battery 71. The other side of the C battery is connected to the filament of the tube 5. The connections of the primary 72 of this last mentioned audio frequency transformer will be described hereinafter.

The plate of the tube 5 is connected to one side of the primary 73 of a radio frequency transformer. The other side of the primary 73 is connected by means of a conductor 74 to one side of the primary 65 of the first audio frequency transformer. The other side of such primary 65 is connected to the busbar 57. A bypassing condenser 75 is connected across the terminals of the primary 65 in order to bypass radio frequency energy. The secondary 76 of the radio frequency transformer between the tubes 5 and 6 has its terminals connected to the grid and filament of the tube 6. This secondary is also bridged by a tuning condenser 77. The plate of the tube 6 is connected through the primary 78 of a radio frequency transformer to the busbar 57. The secondary 79 of such transformer is connected to the grid and filament of the detector tube 7, a suitable grid condenser and leak being employed, as indicated. The plate of the tube 7 is connected by means of conductor 80 to one side of the primary 72 of the second mentioned audio frequency transformer.

The other side of this primary is connected to the point 81 of the B battery to secure the requisite voltage for the detector tube. Preferably, a relatively large condenser 82 is bridged across the terminals of the primary 72, as indicated.

The tube 3, previously described, has its plate connected to one terminal of the primary 66 of the radio frequency transformer between the tubes 3 and 4. The other side 5 of this radio frequency transformer is connected by means of the conductor 83 to one side of the primary 84 of the last audio frequency transformer. The other side of this primary is connected to the busbar 57. The 10 secondary 85 of this last audio frequency transformer is connected to the grid and filament of the power tube 8, a suitable biasing battery, indicated by the reference character C being interposed in this circuit.

15 The plate of the tube 8 is connected through an audio frequency choke coil 86 to the point 87 of the B battery to secure the requisite voltage for the tube 8. The terminals of the coil 86 are also connected through a suitable 20 stopping condenser 88 to the telephone receiver, or loud speaker or other translating device 89 as previously described.

In operation, the radio frequency energy is passed successively through the tubes 1, 2, 25 3, 4, 5, and 6. From the tube 6, this amplified radio frequency energy is passed to the grid circuit of the detector tube 7. The audio frequency energy from the tube 7 passes through the primary 72 of the audio frequency transformer previously described. The secondary 70 of this audio frequency transformer passes audio frequency energy to the grid of the tube 5, the biasing battery 71 holding the negative charge of the grid of the 30 tube 5 at the desired point. The plate circuit of the tube 5 includes the primary 65 of the first described audio frequency transformer. The secondary of this transformer passes audio frequency to the grid of the tube 3. 40 A C battery 64, similar to the battery 71, is employed for this tube. The plate circuit of the tube 3 includes the primary 84 of the last audio frequency transformer.

Further, it is to be noted that this primary 45 84 is bridged by a bypass condenser 90 in order to pass radio frequency energy to the busbar 57. The secondary 85 of the last audio frequency transformer supplies the grid circuit of the power tube.

50 It will be seen that in this form of the invention the audio frequency energy from the detector is first passed to the tube 5, from thence to the tube 3, and thereafter to the power tube 8. In each case, the audio frequency energy is selectively passed only 55 through the untuned tubes. It is not passed through the grid circuits of the tuned tubes. Consequently, the tuned tubes are not loaded up with the audio frequency energy in either 60 form of the invention and the untuned tubes alone are called upon to amplify the audio frequency energy in addition to some amplification of the radio frequency energy passed through these tubes. The net result of this 65 method of handling the audio and radio fre-

quency energy, in the two forms of the invention disclosed, is that the tuning is maintained sharp and the tuned circuits are not called upon to carry audio frequency energy. The tubes associated with the untuned circuits alone carry the audio frequency energy. In addition to this, inasmuch as the untuned tubes are interposed between the tuned tubes, it is apparent that radiation from the antenna is prevented. The system as a whole, 70 cannot be thrown into oscillation during receiving and consequently, the antenna will not radiate. 75

It is apparent therefore that a highly efficient and novel mode of radio reception has 80 been provided by this invention and one which will not disturb other nearby receiving systems.

It is also apparent from an examination of Figures 1 and 2, that relatively simple connections may be employed and a small number of busbars. Further than this, only a 85 small number of terminals are required for the entire set.

In addition to this, a very accurate tuning 90 can be secured with the utmost facility with either form of the invention.

It is to be distinctly understood that although vacuum tubes having input and output circuits have been shown, that obviously 95 other forms of amplifying devices having input and output circuits could be used without departing from the spirit of this invention.

It is to be distinctly understood that other modes of coupling the tubes may be employed 100 and other changes may be made without departing from the spirit of this invention and therefore it is intended that the description and drawings be interpreted as illustrative rather than limiting as the scope of the invention 105 is to be determined only as set forth hereinafter in the appended claims.

I claim:

1. In a radio receiving system, the combination of a plurality of tuned circuits including amplifying devices and a plurality of untuned circuits including amplifying devices, and means for reflexing audio frequency energy only through the amplifying devices associated with the untuned circuits. 110

2. In a radio receiving system, the combination of a series of alternately tuned and untuned circuits including amplifying devices, and means for reflexing audio frequency energy through the amplifying devices associated with the untuned circuits. 115

3. In a radio receiving system, the combination of a plurality of vacuum tubes having coupled grid and plate circuits, the grid circuits of certain of said tubes being tuned and the grid circuits of other of said tubes being untuned, certain of said untuned circuits being located between tuned circuits, and means for reflexing audio frequency energy through the tubes having untuned grid circuits. 120

4. A radio receiving system comprising means for collecting radio frequency energy, a vacuum tube having an untuned grid circuit connected to said collecting means, a second vacuum tube having a tuned grid circuit supplied from said first tube, a third vacuum tube having an untuned grid circuit supplied from said second tube, a detector tube, means coupling the output of said detector tube with said third tube, and a translating device operated from said tubes.

5. A radio receiving system comprising means for collecting radio frequency energy, a vacuum tube having an untuned grid circuit associated with said collecting means, a second vacuum tube having a tuned grid circuit supplied from said first tube, a third vacuum tube having an untuned grid circuit supplied from said second tube, a detector tube, means coupling the output of said detector tube with said third tube, and means for reflexing audio frequency energy through one of the tubes having an untuned grid circuit.

6. In a radio receiving system, the combination of a plurality of amplifying devices connected in cascade, said devices having input and output circuits, a plurality of said input circuits being tuned and a plurality of said input circuits being untuned, one of said devices being a detecting device, the output circuit of said detecting device being reflexed through the untuned input circuits of certain of said amplifying devices.

7. A radio receiving system comprising means for collecting radio frequency energy, a vacuum tube having a grid circuit connected to said collecting means, a second vacuum tube having a tuned grid circuit supplied from said first mentioned tube, a third vacuum tube having an untuned grid circuit supplied from said second vacuum tube, an audio frequency transformer having its secondary connected to the grid and filament of the third tube, a detector having its input circuit controlled from the output circuit of said third tube, said detector having its output circuit connected in series with the primary of said audio frequency transformer, and a translating device controlled from the output circuit of said third tube.

8. A radio receiving system comprising means for collecting radio frequency energy, a vacuum tube having its grid circuit connected to said collecting means, a second vacuum tube having a tuned grid circuit supplied from said first mentioned tube, a third vacuum tube having an untuned grid circuit supplied from said second tube, a fourth vacuum tube having a tuned grid circuit supplied from said third tube, a fifth vacuum tube having an untuned grid circuit supplied from said fourth tube, a sixth vacuum tube having a tuned grid circuit supplied from said fifth tube, a detector having a grid circuit supplied from said sixth tube, an audio frequency

transformer having its primary connected to the output circuit of said detector and having its secondary connected to the grid and filament of said third tube, a second audio frequency transformer having its primary connected in circuit with the plate of said third tube and having its secondary connected to the plate and filament of said fifth tube, a third audio frequency transformer having its primary connected in circuit with the plate of said fifth tube, an eighth vacuum tube having its filament and grid connected to the secondary of said third audio frequency transformer, and a translating device supplied from the plate of said eighth tube.

In testimony whereof, the signature of the inventor is affixed hereto.

WILLIAM TURNOR LEWIS.
